PULVERIZING OR GRINDING MILL

Application filed November 22, 1928. Serial No. 321,206.

Our invention relates to improvements in pulverizing or grinding mills, and has particular reference to improvements in the rotatable pushing means, which serves to drive the grinding balls.

In accordance with our invention, a rotatable yoke is provided which is secured to and driven by the usual drive shaft. This yoke has outwardly projecting arms, preferably formed integral therewith. These arms have their central longitudinal axes off-center with respect to the yoke and preferably substantially parallel with tangents to the yoke. This arrangement is preferred, whereby there will be sufficient space for the grinding balls. Each arm carries an arm-extension, pivoted thereto, and preferably arranged in end-to-end relation to the same. A spring is confined between portions of the arm and arm-extension, to oppose the swinging movement of the arm-extension in a direction opposite to the direction of travel of the yoke. A pusher element is preferably rotatably mounted upon the arm-extension, so that it is adapted to turn upon its longitudinal axis, during its rotation with the yoke. This pusher element slidably contacts with the adjacent grinding ball, and its contact face is spherically curved and convex, or tapers forwardly, to coact therewith. By having the pusher element yieldingly supported, undue strains and hammering action between the pusher element and the ball, is eliminated, particularly upon starting the mill, and liability of the arms of the yoke being broken off also eliminated, which frequently occurs where the pusher elements are rigidly carried by the arms. The yielding support for the pusher element also permits of a more free rotation of the grinding ball. Further, the pusher element being rotatable upon its axis, the contacting surfaces between the pusher element and the grinding ball are constantly shifting and wearing or scoring of the grinding ball or pusher element are greatly reduced. As the grinding ball moves out slightly, due to the wearing down of the grinding ring, the contacting surfaces of the pusher element and grinding ball automatically adjust themselves, without injury to the

contacting parts, which is rendered possible, to a considerable extent, by the rotation of the pusher element upon its axis. The minimum contact surfaces between the grinding ball and pusher element, also permits of the free restricted radial movements of the grinding ball due to the shifting of the ball by the varying thicknesses of the material being ground.

In the accompanying drawings, forming a part of this specification, and in which like numerals are employed to designate like parts throughout the same,

Figure 1 is a central vertical longitudinal section through a mill embodying our invention,

Figure 2 is a horizontal section taken on line 2-2 of Figure 1,

Figure 3 is a longitudinal section taken on line 3-3 of Figure 2,

Figure 4 is a plan view of the yoke and associated elements,

Figure 5 is a side elevation of the same,

Figure 6 is an enlarged plan view of one of the arms and arm extension and associated elements,

Figure 7 is a plan view of the same, and,

Figure 8 is a transverse section taken on line 8-8 of Figure 6.

The pushing means or yoke and associated elements constituting the principal feature of the present invention, are particularly well adapted for use in connection with the pulverizing or grinding mill, shown in Letters Patent No. 922,468, granted under date of May 25, 1909, to J. W. Fuller, Jr. This mill embodies generally a casing 10, within which is arranged a grinding ring 11, having a transversely curved annular recess 12, within which travel the grinding balls 14. An upper casing section 15 is arranged upon the casing 10 and a screen 16 is disposed within the casing section 15 and spaced therefrom, with a coarser protecting screen 17, disposed inwardly of the first named screen. The pulverized or ground material which passes the screen 16 discharges into a passage 18, and descends through the passage 19 and finally discharges through an outlet 20. The numeral 21 designates a feed hopper, which dis-

charges the material into the upper portion of the casing 15, inwardly of the screen 17.

The numeral 22 designates a vertical drive shaft, journaled in bearings 23 and 24, and driven by a pulley 25. The construction thus far described is identical with that shown in Patent No. 922,468, above referred to, and is thought to be sufficient for a proper understanding of the present invention.

Our improved pushing means or yoke embodies a tubular hub 26, arranged upon the drive shaft 22, to rotate therewith. Extending outwardly from the hub 26 are arms 27, preferably formed integral therewith. The longitudinal axes of these arms are off-center with respect to the hub 26, and are preferably parallel with tangents to the hub. This arrangement is preferred, to provide sufficient space for the grinding balls, as will be apparent. Each arm 27 is provided in its forward face with a recess 28, for receiving therein an apertured knuckle 29, preferably formed integral with an arm-extension 30. The knuckle forms with the arm-extension shoulders 31. The knuckle 29 is apertured, for receiving a pivot pin 32, also passing through openings 33, formed in the sides of the arm 27. The arm-extension 30 is provided with a rearwardly projecting overhanging circumferentially extending head 34, integral therewith, and carrying an inwardly projecting lug 35, preferably integral therewith. A co-acting lug 37 is carried by the circumferentially extending part of the arm 27, disposed opposite the head 34, and is preferably formed integral therewith, and arranged opposite the lug 35. The arm-extension 30 and its head 34 are arranged in end-to-end relation to the arm 27, as shown. A suitably stiff compressible substantially radial coil spring 36 is disposed rearwardly of the arm-extension and confined between the end of the arm 27, and the overhanging head 34, with the retaining lugs 35 and 37 passing into the ends thereof. It is thus seen that the action of the circumferentially extending head 34 retains the radial spring 36 in place, and there is no tendency for the spring to partake of lateral displacement due to centrifugal force.

The numeral 38 designates a pusher element, which is adapted to rotate upon its axis, and be bodily rotated by the rotating yoke. For this purpose, the pusher element 38 is provided with a cylindrical shank 39 preferably formed integral therewith, and this shank is rotatably mounted within a cylindrical recess or opening 40 formed in the forward side of the arm-extension 30. The pusher element 38 is arranged to engage with the adjacent grinding ball 14, and this grinding ball is confined between the pusher element and the next forward arm 27. There is a slight clearance between the ball and the adjacent forward arm 27, when the ball is

contacting with the pusher element, and the mill is in operation, but this clearance is not sufficient to permit the shank 39 to be withdrawn from the recess 40, or to permit the arm-extension 30 swinging forwardly sufficiently, to free the spring 36. The forward swinging movement of the arm-extension 30 is also limited by the shoulder 31 contacting with the end of the arm 27, and the clearance between this shoulder and the end of the adjacent arm is the same as the clearance between the grinding ball and the adjacent forward arm, as explained.

The forward contacting end of the pusher element 38 is preferably spherically curved and convex, or tapered forwardly, and this convex surface slidably contacts with the grinding ball. The pusher element 38 is preferably formed of steel and has its convex contacting face hardened. As illustrating one way in which the hardening may be effected, we contemplate placing a covering 41 of high speed tool steel upon the pusher element, which may be welded thereto, although the convex face may be hardened by any suitable means. By virtue of the convex or tapered face of the pusher element, the minimum contact surface is afforded between the pusher element and the grinding ball, and this permits of the free spinning of the grinding ball, and this spinning action of the ball is aided by the yielding support of the pusher element.

The numeral 45 designates a fan or blower as a whole, including a lower ring 46, carrying outwardly projecting radial lugs 47, bolted to the arms 44, as shown at 48. Formed integral with the ring 46 are spaced vertical arms 49, carrying upper vertically arranged blades or paddles 50, integral therewith. The blades 50 are disposed at the leading edges of the vertical arms 49 and are further connected therewith by tapered webs 51, integral therewith. The vertical blades 50 rotate adjacent to the screens 16 and 17 and serve to throw the ground material through or toward the same. The numeral 52 designates lower elevating blades or paddles which are inclined and have their lower ends extending in an elevation beneath the lower ends of the vertical blades 50. The lower elevating blades 52 are preferably provided at their outer edges with upstanding longitudinal flanges 53. The blades 52 are formed integral with the ring 46, and webs 53 reinforce and connect these parts, and are formed integral therewith. The elevating blades 52 operate above and near the grinding balls 14 and serve to raise the powdered or ground material, which is brought into the path of travel of the vertical centrifugal blade 50 and thrown thereby toward the screen 16.

In operation of the mill, the material is fed into the central portion of the same through the hopper 21, and passes to the grinding

balls 14, traveling upon the grinding ring. The shaft 22 is driven at a suitably high speed, and the elevating blades serve to draw the ground or powdered material upwardly and through the same into the path of travel of the vertical or centrifugal blades 50, which in turn throw the same toward or through the screens 16 and 17. The grinding balls are propelled by the pusher elements 38. These balls rotate rapidly upon the grinding ring, and must be free to turn or spin. The free action of the grinding balls depends greatly upon the area of contact between the same and the pusher elements. It is desired to have these areas of contact reduced to the minimum, and for this reason the contact faces of the pusher elements are convex.

It is to be understood that the form of our invention, herewith shown and described, is to be taken as a preferred example of the same, and that various changes in the shape, size and arrangement of parts, may be resorted to without departing from the spirit of our invention, or the scope of the subjoined claims.

Having thus described our invention, we claim:—

1. In a grinding mill, a casing, a grinding ring arranged within the casing, grinding balls operating upon the grinding ring, a drive shaft extending between the grinding balls, pusher elements having convex ball engaging surfaces spherically curved in all directions, and a support carrying the pusher elements and driven by the shaft.

2. In a grinding mill, a casing, a grinding ring arranged within the casing, grinding balls operating upon the grinding ring, a rotatable support arranged within the casing, and pusher elements rotatably mounted upon the support to turn upon their axes with relation thereto and having convex ball engaging surfaces spherically curved in all directions.

3. In a grinding mill, a casing, a grinding ring arranged within the casing, grinding balls operating upon the grinding ring, a rotatable support arranged within the casing, and pusher elements rotatably mounted upon the support to turn upon their axes with relation thereto and arranged to contact with the grinding balls, the longitudinal axes of the rotatable pusher elements extending circumferentially of the support.

4. In a grinding mill, a casing, a grinding ring arranged within the casing, grinding balls operating upon the grinding ring, a rotatable support arranged within the casing, generally radial yielding supporting devices carried by the rotatable support, and separate pusher elements rotatably mounted upon the yielding supporting devices and arranged to contact with the grinding balls, said pusher elements having their axes of rotation extending generally circumferentially.

5. In a grinding mill, a casing, a grinding

ring arranged within the casing, grinding balls operating upon the grinding ring, a drive shaft extending between the grinding balls, a yoke carried by the drive shaft and embodying outwardly extending arms, arm-extensions pivotally connected with said arms, springs arranged between portions of the arms and arm-extensions and separate rotatable pusher elements carried by the arm-extensions for engagement with the grinding balls.

6. In a grinding mill, a casing, a grinding ring arranged within the casing, grinding balls operating upon the grinding ring, a drive shaft extending between the grinding balls, a yoke carried by the drive shaft and embodying generally radially extending arms, generally radially extending arm-extensions arranged in end-to-end relation to said arms and having pivotal connection therewith to swing in the plane of rotation of said arms, said arm-extensions having circumferentially extending heads, generally radially disposed compressible coil springs arranged between the circumferentially extending heads and said arms, and pusher elements carried by the forward side of said arm-extensions.

7. In a grinding mill, a casing, a grinding ring arranged within the casing, grinding balls operating upon the grinding ring, a drive shaft extending between the grinding balls, a yoke carried by the drive shaft and embodying generally radially extending arms, said arms having recesses formed therein, generally radially arm-extensions arranged in end-to-end relation to said arms and having knuckles extending into said recesses, means pivotally connecting the knuckles and said arms, circumferential heads carried by the arm-extensions and arranged upon the rear side thereof, lugs carried by the heads and said arms, generally radial compressible coil springs arranged between the heads and said arms and receiving the lugs in the opposite ends thereof, and a pusher element carried by the forward side of each arm-extension.

8. In a grinding mill, a casing, a grinding ring arranged within the casing, grinding balls operating upon the grinding ring, a drive shaft extending between the grinding balls, a yoke carried by the drive shaft and embodying outwardly extending arms, said arms having recesses formed therein, arm-extensions arranged in end-to-end relation to said arms and having knuckles extending into said recesses, means pivotally connecting the knuckles and said arms, overhanging heads carried by the arm-extensions and arranged upon the rear side thereof, lugs carried by the heads and said arms, compressible coil springs arranged between the heads and said arms and receiving lugs in the opposite ends thereof, and a pusher element rotatably

mounted upon the arm-extension and arranged to engage the adjacent grinding ball.

9. In a grinding mill, a casing, a grinding ring arranged within the casing, grinding balls operating upon the grinding ring, a drive shaft extending between the grinding balls, a yoke carried by the drive shaft and embodying outwardly extending arms, said arms having recesses formed therein, arm-extensions arranged in end-to-end relation to said arms and having knuckles extending into said recesses, means pivotally connecting the knuckles and said arms, overhanging heads carried by the arm-extensions and arranged upon the rear side thereof, lugs carried by the heads and said arms, compressible coil springs arranged between the heads and said arms and receiving lugs in the opposite ends thereof, and a pusher element rotatably mounted upon the arm-extension and having a convex face to engage with the adjacent grinding ball.

10. In a grinding mill, a casing, a horizontal grinding ring within the casing, grinding balls engaging the ring, a horizontally rotating support, pusher elements pivotally mounted upon the support to swing horizontally with relation thereto and engaging the grinding balls, and yielding means to oppose the swinging movement of the pivoted pusher elements in one direction.

11. In a grinding mill, a casing, a horizontal grinding ring within the casing, grinding balls engaging the ring, a horizontally rotating support, pusher elements pivotally mounted upon the support to swing horizontally with relation thereto and engaging the grinding balls, said pusher elements having forwardly tapered faces for providing a small area of contact with the balls, and springs for opposing the rearward swinging movement of the pusher elements upon their pivots.

12. In a grinding mill, a casing, a grinding ring within the casing, grinding balls operating upon the grinding ring, a rotatable support, and pusher elements carried by the rotatable support and having convex ball engaging surfaces spherically curved in all directions so that they will afford the minimum contact areas with the grinding balls.

13. In a grinding mill, a casing, a grinding ring within the casing, grinding balls operating upon the grinding ring, a rotatable support arranged within the casing, pivoted arms carried by the support, springs to oppose the swinging movement of the arms upon their pivots, and pusher elements carried by the arms and provided with forwardly tapering contact surfaces for engagement with the balls, said forwardly tapering contact surfaces co-acting with the spring-pressed pivoted arms for effecting a spinning movement of the balls.

14. In a grinding mill, a casing, a grind-

ing ring within the casing, grinding balls engaging the ring, a rotatable support within the casing, arms pivoted to the support, yielding means to oppose the swinging movement of the arms upon their pivots, and pusher elements carried by the arms and having convex contact faces to engage with the grinding balls, said convex contact faces co-acting with the pivoted spring-pressed arms to effect a spinning movement of the balls.

15. In a grinding mill, a casing, a grinding ring within the casing, grinding balls engaging the ring, a rotatable support within the casing, arms pivoted to the support, springs to oppose the movement of the arms upon their pivots, and pusher elements carried by the pivoted arms and having convex faces which are harder than the body portion of the pusher elements, said convex contact faces co-acting with the spring-pressed pivoted arms to effect spinning movement of the balls.

16. In a grinding mill, a casing, a grinding ring within the casing, grinding balls engaging the ring, a rotatable support within the casing, generally radial arms pivoted to the support to swing in the plane of rotation of the support, resilient means to oppose the swinging movement of the arms, and pusher elements rotatably mounted upon the forward side of the arms and having their axes of rotation extending circumferentially, said pusher elements having forwardly tapering contact faces to engage with the grinding balls, the forwardly tapering contact faces co-acting with the pivoted arms for effecting a spinning movement of the balls.

17. In a grinding mill, a casing, a grinding ring within the casing, grinding balls engaging the ring, a rotatable support within the casing having generally radial arms, generally radial arm extensions pivoted to the first named arms to swing in the plane of rotation of the support, said arm extensions having circumferentially extending heads disposed opposite the parts of said arms, generally radial springs held between said parts and the circumferentially extending heads, and pusher elements arranged upon the forward sides of the arm extensions and pivoted thereto so that their axes of rotation extend generally circumferentially, said pusher elements having convex contact faces to engage with the balls.

In testimony whereof we affix our signatures.

DAVID J. UHLE.
JOSEPH V. DURNIN.
